SPARK PLUG

Filed July 29, 1927

FIG. 1

FIG. 2

INVENTOR.

EARL E. BIDWELL

BY

E. G. Charles
ATTORNEY.

UNITED STATES PATENT OFFICE

EARL E. BIDWELL, OF WICHITA, KANSAS

SPARK PLUG

Application filed July 29, 1927. Serial No. 209,362.

This invention relates to spark plugs for internal combustion engines and among the objects thereof may be mentioned the provision of means for providing a spark plug 5 with an ignition chamber within the shell of such form that when the fuel is initially combusted in the spark plug chamber, it will discharge into the combustion chamber of the motor with sufficient force to create a turbulence of the fuel in the combustion chamber of the motor at the time of ignition and by increasing the rate of combustion of the fuel in the combustion chamber (that is, cutting down the lag of combustion) a marked 10 increase in the "pick-up" of the motor and in the general power efficiency thereof will be assured. Because of the more perfect combustion, higher speed can be obtained, while at the same time the fuel consumption is less. 15 The consumption chamber in the spark plug shell is of such form that it rids itself of carbon, oil and the like at each explosion, and due to a Venturi action at the restricted discharge orifice, the burning gases from the 20 chamber within the plug not only ignite the gases in the combustion chamber of the engine but they also cause appreciable turbulence. The temperature of the positive electrode and the insulator therefor is constantly high enough to vaporize the oil so that 25 it is consumed as fuel. Any oil which enters the combustion chamber will contact with the hot end of the electrode which acts as a baffle and causes the oil to heat to the vaporizing 30 temperature. So much so I have found in actual practice that it has become necessary to retard the spark on account of the rapid combustion which takes place in the combustion chamber of the engine. 35 I have found that it is quite important to have the electrode off-set with respect to the outlet orifice of the combustion chamber because the outlet orifice also serves as an inlet orifice for the fresh gas and in the event that 40 oil enters the chamber, it will not wet the electrodes or porcelain because it will never get past the baffle on the end of the electrode, which would happen if the electrodes were in line with the orifice. I have, also, found 45 it to be advantageous to set the negative electrode, (that is, the one attached to the shell) in line with the positive electrode, as for example in the case of plugs used in racing-automobile and airplane engines, because when the engine speeds up, the positive electrode will expand, automatically shortening the gap between the two electrodes which is desirable under certain conditions. I have, also, provided means for maintaining the insulating porcelain and therefore, the positive 55 electrode in proper spaced relation with the shell. Other objects and advantages of the invention will be referred to hereinafter, reference being had to the accompanying drawings in which: 60

Fig. 1 is an elevation of the spark plug, partly in section.

Fig. 2 is an end view taken on line 2-2 in Fig. 1 and

Fig. 3 is a longitudinal sectional view, 70 showing a different position of the negative electrode to form a spark gap.

The shell 1 is shown as provided with the usual externally threaded end 2 whereby the plug can be screwed into the engine block. 75 The opposite end of the shell has an internally threaded socket to receive a packing gland 3 which carries the insulation 4. The shell has a chamber 5 at its inner end into which the porcelain A projects. 80

Axially extending through the insulator is the positive electrode 6, the outer threaded end of which receives a jam nut 8, which cooperates with the binding nut 7 to hold the end of the feed wire. Under the jam nut 8 is a washer 8' to prevent leakage at the outer end of the porcelain. The electrode 6 is provided at its inner end with a cup-shaped head or disc 9 which is drawn tightly against the insulator by screwing up the nut 8. The head 9 constitutes the effective inner end of the insulator 6 for co-operation with the negative electrode to be referred to hereinafter. B and C are two annular shoulders in spaced 85 relation within the shell. Two copper washers 10 and 10' abut against the shoulders and hold the insulator or porcelain in proper spaced relation inside the shell. These washers flex when the porcelain expands or contracts. 11 is the restricted inlet and outlet 90

100

orifice for the chamber 5 and at its outer end it is slightly flared, as at 12, to provide a dispersive effect for the combusted gases as they are forced out through the orifice due to combustion. The injection effect causes the burning gases from chamber 5 to pass into the combustion chamber at high velocity and at about the time it penetrates the fuel charge in the combustion chamber it starts to expand in all directions to set up a violent turbulence in the gases in the combustion chamber of the engine and to cause immediate ignition of all of the gases in the combustion chamber instead of permitting the usual lag of ignition incident to the use of the ordinary spark plug where the spark initially ignites the gases within the combustion chamber at a point. The negative electrode 13 is off-set out of axial alignment 5 with the orifice 11 and terminates in spaced relation with the edge 14 of the head 9 which is relatively sharp compared with the diameter of electrode 13, the head 9 having sufficient material to prevent its becoming hot 10 enough to cause pre-ignition independent of the spark. Since the negative electrode 13 carried by the shell is spaced axially of the plug from edge 14, and since the electrode 13 is carried by the cooled wall of the engine 15 block, the expansion of the porcelain A and electrode 9 will cause the spark gap to be decreased as the motor heats up. As a result when the engine is running at high speed, there will be a shorter gap between the head 20 9 and the electrode 13 and at low speed this gap will be slightly increased due to dropping of temperature in the engine. It will also be observed that the annular head of the positive electrode, by loosening packing gland 25 3 and revolving the porcelain A with electrode 3, 9, 14 can be turned from time to time to present new contact points to the positive electrode.

On the intake stroke of the piston a slight 45 vacuum will be created in chamber 5 so that on the compression stroke a clean charge will be introduced into combustion chamber 5 ready to fire when the piston reaches the top of the compression stroke and the timer 50 causes the spark to jump across the gap between the electrodes in the shell. Then, during the down stroke of the piston, the burnt gases will be violently introduced into the combustible gases in the cylinder as previously explained. In Fig. 3 the electrode 13 is introduced through the side of the shell, but its effective end is in line with the head 9 in substantially the same manner as the electrode 13 shown in Fig. 1.

60 It will be noted that the bottom of the chamber 5 has symmetrically formed wall surface to bend the gases in easy stream lines so that no carbon can form on shoulders or ledges inside the chamber on account of the 65 velocity of the gases escaping from this cham-

ber wiping these smooth walls free from all foreign matter.

The proportional size and the shape of chamber 5 is important and is the result of many experiments. The space about the insulator 4, in the chamber must not be too great and the electrode 14 must be located well below the top of the chamber. The space shown between the electrode 14 and the orifice 11 is about the maximum permissible. 70 75

Minor changes may be made in the physical embodiment of the invention and in the portion of parts within the scope of the appended claims without departing from the spirit 80 of the invention.

What I claim and desire to secure by Letters-Patent is:

1. A spark plug comprising a shell having a chamber with a restricted, unobstructed, opening through which fresh fuel may pass 85 into the chamber and burning gases may pass from the chamber, the wall of the chamber about the opening curving toward the opening, an electrode extending into the chamber, an insulator between the shell and the electrode, a second electrode in the chamber above said orifice and forming a spark gap with said first named electrode said gap offset with respect to said opening. 90

2. A spark plug comprising a shell having a combustion chamber therein with an inlet and outlet orifice, an electrode and insulator cooperating with the shell and extending into said chamber in line with said orifice, and an electrode carried by said shell and extending into said chamber and having a gap laterally offset from said orifice and spaced from said first-named electrode in a direction lengthwise of the axis of the plug. 95 100

3. A spark plug comprising a shell having an electrode insulated therefrom and comprising a part which is off center with respect to said shell, said shell containing a combustion chamber having a single inlet and outlet orifice in line with said electrode, the inner end of said electrode being of greater diameter than the diameter of said orifice, and an electrode in said chamber spaced from said part of said first-named electrode in a direction lengthwise of the axis of the plug, whereby the gap between the two electrodes will be varied by the expansion and contraction of said first-named electrode. 110 115

4. In a spark plug a shell containing a chamber axially positioned therein, an aperture in said shell in vertical alignment with said chamber, said chamber converging to said aperture, an insulation member having an electrode with a disk axially positioned within said chamber, and a projection on said shell with the inner end of said projection in close proximity to the rim of said disk, whereby a spark gap laterally offset relative to the axis of said aperture is formed. 120 125

5. A spark plug comprising a shell having 130

a chamber provided with a restricted, unobstructed, aperture, a dished electrode in said chamber, and a second electrode cooperating with the annular rim of the dished portion of
5 said dished electrode.

6. A spark plug comprising a shell, an electrode, an insulator between said shell and said electrode, said shell containing a chamber and said electrode extending into said
10 chamber, said chamber having a restricted, unobstructed opening, with the wall of said chamber converging toward said opening and through which opening the fresh fuel may pass into said chamber and burning gases pass
15 therefrom, and an electrode in said chamber complementary to said first-named electrode and forming therewith a spark gap offset laterally with respect to said opening in said chamber and spaced from said first-named
20 electrode in a direction lengthwise of the axis of the plug.

In testimony whereof I affix my signature.
EARL E. BIDWELL.
